(57) **ABSTRACT**

A glove particularly useful for cycling includes a plurality of finger elements a thumb element a dorsal side panel and a palmar side panel. The finger elements cover the fingers the thumb elements cover a thumb the dorsal side panel covers a back or dorsal side of the hand and the palmar side panel covers a palm of the hand. Shock absorbing pads are provided on the palmar side of the glove to extend along opposed sides of the ulnar nerve when in a use condition. Moreover one of the ulnar protective pads is placed generally between the ulnar and the median nerves and thereby off loads the stress on the ulnar nerve in the wrist area of the wearer when a wearer is gripping objects such as the handle bars of a bicycle or the like.

FIG. 1

FIG. 2

FIG. 2A

FIG. 3

FIG. 4

FIG. 5

FIG. 6

1
CYCLING GLOVE

BACKGROUND OF THE INVENTION

(a) Field of the Invention

This invention relates to gloves for the human hand and particularly for the protection of the ulnar and median nerves in the wrist area of the human hand. More particularly, this invention relates to a protective glove for use in sports for applications where the hands of the wearer are exposed to high impact or stress over prolonged periods of time such as, for example, as in the sport of long distance cycling.

(b) Description of Prior Art

Glove construction for protection of the human hand is well known. In addition, there are a number of patents which teach gloves claimed to be particularly useful in the playing of sports. Moreover, there are a number of patents which teach gloves claimed to be particularly useful for long distance cycling and in the protection for the median and ulnar nerves of the human hand. For example, U.S. Pat. Nos. 6,704,939; 6,216,276; and 5,581,809 teach padding used in the palm areas of the hand which are conducive for use in weight lifting and cycling.

The median and ulnar nerves in the hand pass through separate canals within the wrist area of the hands and when the wrist area of the hand is subjected to stress on these nerves over an extended period of time, the nerves can become involved and potentially suffer a condition such as carpal tunnel syndrome. This prolonged exposure to stress is prevalent in long distance cycling.

For example, U.S. Pat. No. 6,006,751 is directed to a glove for allegedly preventing carpal tunnel syndrome and teaches resilient protective padding which extends along opposed sides of the median nerve along the wrist area and into the palm of the wearer.

U.S. Pat. No. 6,845,514 is directed to a glove with pads for protecting the median and ulnar nerve of the hand and teaches devices to hold these pads in place in relation to the median and ulnar nerves. Specifically, the protective pads are positioned so that one of the pads extends along the metacarpals of the thumb in an area distal to the scaphoid and along the metacarpal of the index finger. A second pad extends along the metacarpal of the small finger along the ulnar nerve terminating at the pisiform.

However, there is a continued need for protective gloves which are specifically designed for off loading the stress exerted upon the ulnar and median nerves in the wrist area.

SUMMARY OF THE INVENTION

It is an object of the present invention to provide a glove for use in sports and occupational applications where the hands of the wearer are exposed to hand gripping functions for extended periods of time such as, for example, long distance cycling.

It is another object of the present invention to provide a protective glove which is constructed to enable or facilitate easy closure of the glove when in use.

It is a further object of the present invention to provide a protective glove which includes zones free of padding at selected areas to enhance the closure and use of the glove in a closed or semi-closed condition.

More particularly, the present invention provides a protective glove having a palm side, a dorsal side, a thumb stall, and plurality of finger stalls for receipt of the index finger, the long finger, the ring finger and the small finger, with an opening therein for receiving a person's hand therethrough.

2

The palm side of the glove is provided with a palmar side panel which includes shock absorbing pads located to be along opposed sides of an ulnar nerve in the wrist area of a human hand. The shock absorbing pads may include a first shock absorbing pad positioned along the medial side to the proximal end of a metacarpal of a little finger of the human hand and adjacent to or over the pisiform in the wrist area and a second shock absorbing pad positioned to be between the median and ulnar nerves in the wrist area of the hand and over a portion of the capitate, the hamate, and the lunate bones in the wrist.

Other objects and advantages of the present invention will appear from the following description and appended claims, reference being had to accompanying drawings forming a part of a specification wherein like reference characters designate corresponding parts in several views.

BRIEF DESCRIPTION OF THE DRAWINGS

A better understanding of the invention will be had upon reference to the following description in conjunction with the accompanying drawings in which like numerals refer to like parts throughout the several views and wherein:

FIG. 1 is a schematic representation of the bones and nerves of the right side human hand shown in palm side detail;

FIG. 2 is a palm side view of a preferred embodiment of the present invention showing the palmar side details of a glove for a right hand;

FIG. 2A is a dorsal side view of the glove of FIG. 2;

FIG. 3 is a palmar side schematic representation of a right human hand showing the location of the median and ulnar nerves and the protective pad details in relation to these nerves;

FIG. 4 is a palmar side view of another embodiment of the present invention showing the palmar side details of the glove;

FIG. 5 is a sectional view taken along line 5-5 of FIG. 2; FIG. 6 is a sectional view taken along line 6-6 in FIG. 4.

DESCRIPTION OF THE PREFERRED
EMBODIMENTS

FIG. 1 is a schematic anatomical view of the bones of a right human hand 10 looking at a palm side. Shown are the radius 20, ulna 21, radiocarpal joint (RC) 23, distal radio ulnar joint (DRUJ) 22, wrist 12, thumb 64, index finger 65, long finger 66, ring finger 67, and small finger 68. A carpus comprising eight carpal bones which are shown in FIG. 1 includes the capitate bone 97, the pisiform 99, the hamate bone 71 with its hook-like protrusion, the scaphoid 24 and the lunate 25.

The thumb 64 is comprised of the distal phalanx 51, the interphalangeal joint (IP) 46, proximal phalanx 41, metacarpalphalangeal joint (MCP) 36, metacarpal 31, and carpometacarpal joint (CMC) 26.

The index finger 65 is comprised of the distal phalanx 60, distal interphalangeal joint (DIP) 56, middle phalanx 52, proximal interphalangeal joint (PIP) 47, proximal phalanx 42, metacarpalphalangeal joint (MCP) 37, metacarpal 32, and carpometacarpal joint (CMC) 27.

The long finger 66 is comprised of the distal phalanx 61, distal interphalangeal joint (DIP) 57, middle phalanx 53, proximal interphalangeal joint (PIP) 48, proximal phalanx 43, metacarpalphalangeal joint (MCP) 38, metacarpal 33, and carpometacarpal joint (CMC) 23.

The ring finger 67 is comprised of the distal phalanx 62, distal interphalangeal joint (DIP) 58, middle phalanx 54, proximal interphalangeal joint (PIP) 49, proximal phalanx 44, metacarpalphalangeal joint (MCP) 39, metacarpal 34, and carpometacarpal joint (CMC) 24.

The small finger 68 is comprised of the distal phalanx 63, distal interphalangeal joint (DIP) 59, middle phalanx 55, proximal interphalangeal joint (PIP) 50, proximal phalanx 45, metacarpalphalangeal joint (MCP) 40, and metacarpal 35.

Also as shown in FIG. 1 is a schematic representation of the median and ulnar nerve systems. The median nerve is identified by the numeral 104 and the ulnar nerve is identified by the numeral 102. In the wrist area of the hand, the ulnar nerve 102 is positioned between the pisiform 99 and the lunate 25. Also shown for illustrative purposes is the location for the two shock absorbing pads which are positioned on opposite sides of the ulnar nerve 102 and adjacent to or over the pisiform 99. A first shock absorbing or ulnar protective pad 152 is medial to the ulnar nerve 102 and the second ulnar protective pad 154 is positioned lateral to the ulnar nerve 102 between the ulnar nerve 102 and the median nerve 104. The positioning of pad 152 is along the medial side of the proximal end of the metacarpal 35 of the small finger 68. The positioning for the ulnar protective pad 154 is generally over a portion of the capitate bone 97, the hamate bone 71 and the lunate 25.

As best shown in FIG. 2 is a preferred embodiment of a glove 150 of the present invention, particularly useful in cycling or the like. The glove 150 includes a palmar side panel 151 and a dorsal side panel 153 (FIG. 2A). The panels 151 and 153 are attached along opposite sides with an opening 149 therein to receive the hand 10 therethrough. The glove 150 is provided with a plurality of finger and thumb elements 155a-155e. The finger elements include the small finger element 155a, the ring finger element 155b, the long finger element 155c, the index finger element 155d and the thumb element 155e. All of the finger and thumb elements 155a-155e may include open distal ends exemplified as open distal ends 147a-147e to receive the fingers 65, 66, 67 and 68 of a human hand and the thumb 64 therethrough. The finger and thumb elements 155a-155e are also provided with padding at selected points therealong to protect the pulleys and tendons of the fingers and thumbs. Protective pads 157a, 157b, 157c, and 157d are positioned along the finger elements 155a, 155b, 155c and 155d, respectively, between the distal interphalangeal joints 59, 58, 57 and 56 and the proximal interphalangeal joints 50, 49, 48 and 47, respectively. Also as shown in FIG. 2 shock absorbing or protective pads 159a, 159b, 159c and 159d are positioned to cover the proximal phalanxes 45, 44, 43 and 42 of the small finger 68, the ring finger 67, the long finger 66, and the index finger 65 respectively, and between the proximal interphalangeal joints 50, 49, 48 and 47 and the metacarpalphalangeal joints 40, 39, 38 and 37. Also provided in the preferred glove 150 are expansion zones in the finger elements 155a-155d and identified as expansion zones 161a, 161b, and 161c, said expansion zones including a stretchable material positioned to be over the proximal interphalangeal joints 50, 49, and 48, respectively. The palmar side of the glove is also provided with palmar protective pads 160a and 160b which are positioned to extend across the palmar side of the glove. The palmar protective pads 160a and 160b are positioned to extend transversely of the metacarpals 35, 34, 33 and 32 to protect the nerves and tendons anterior to the metacarpals 35, 34, 33 and 32. An optional space 160c is provided between the pads

160a and 160b and is positioned to extend transversely across the palmar side of the human hand thereby allowing for easier flexion of the hand upon closure. The metacarpalphalangeal joints 40, 39, 38, and 37 are located between each of the finger pads 159a and palm pad 160a thereby allowing for unencumbered use of these joints. The thumb element 155e is also provided with palmar side padding. A thumb shock absorbing pad 156 proximal to the metacarpalphalangeal joint 36 is provided to protect the metacarpal 31 and thumb shock absorbing pad 158 is provided to protect the nerves, pulleys and tendons along the proximal phalanx 41 distal to the metacarpalphalangeal joint 36. In expansion zone 161e, an elastomeric stretchable material is provided over the metacarpalphalangeal joint 36 of the thumb 64. Also, as shown in FIG. 2, the ulnar protective pads 152 and 154 are positioned along opposed sides of the ulnar nerve 102 (FIG. 1).

In FIG. 2A glove 150 includes a dorsal side panel 153 which is attached along its outer periphery 153a to the palmar side panel 151 (FIG. 2).

As shown in FIG. 3, is a schematic representation of the ulnar nerve 102 and median nerve systems 104 of the human hand 10 and the depiction of the protective paddings and specific location of these protective pads 152, 154 on opposed sides of the ulnar nerve system 102 and the median nerve system 104. As best shown in FIG. 3, the ulnar protective pad 152 is positioned medial to the ulnar nerve 102 along the proximal end and generally along the medial side to the metacarpal 35 of the small finger 68. The proximal terminating end of the ulnar protective pad 152 is adjacent to the pisiform 99 but may extend over the pisiform 99. The ulnar protective pad 154 is generally positioned between the ulnar nerve 102 and the median nerve 104 and, as best shown in FIG. 1, extends over a portion of the capitate 97, the hamate 71, and the lunate 25.

Shown in FIG. 4 is another preferred embodiment of the present invention which depicts an additional pad 252 which crosses over the ulnar nerve 102, as best shown in FIG. 6 and discussed hereinafter. The glove 150a is also provided with a plurality of finger elements 165a, 165b, 165c and 165d, as well as a thumb element 165e. The finger elements 165a, 165b, 165c and 165d are provided with distal openings 169a, 169b, 169c and 169d therein to receive fingers 68, 67, 66 and 65 therethrough, respectively. The thumb element 165e is also provided with an opening 169e in the terminating end thereof to receive a thumb 64 therethrough. Palmar protective pads 170a and 170b are provided to extend transversely of the metacarpals 35, 34, 33, and 32 proximal to the metacarpalphalangeal joint 40, 39, 38 and 37 of the finger 68, 67, 66 and 65, respectively. A space 170c between pads 170a and 170b is provided to allow easier movement of the metacarpalphalangeal joints of the fingers when in use. The thumb element 165e is also provided with thumb protective pads 176 and 178. Protective pad 176 is positioned to extend over the thumb metacarpal 31 proximal to the metacarpalphalangeal joint 36 and protective pad 178 extends over the pulleys and tendons of the proximal phalanx 41 distal to the metacarpalphalangeal joint 36. The ulnar protective pad 252 is provided to overlie the protective pads 152 and 154, as best shown in FIG. 6.

Referring now to FIG. 5, FIG. 5 is a cross-sectional view of a section of the glove 150 shown in FIG. 2 showing the relationship between the ulnar protective padding 152 and 154 to the ulnar nerve 102 and the median nerve 104 when placed upon the hand of the wearer. Particularly pad 152 extends along the medial side of ulnar nerve 102 and pad 154 is disposed generally between the ulnar nerve 102 and

the median nerve 104. As shown in FIG. 5 the glove 150 includes an outer palmar side panel 151 which extends over the ulnar protective pads 152 and 154 and also includes an inner glove lining 165 which is the palmar side inner lining of the glove 150. The outer skin of a wearer is identified by the numeral 167.

Shown in FIG. 6 is a cross-sectional view of the glove 150a which is a modification of the glove as depicted in FIGS. 2 and 5. FIG. 6 is a cross-sectional view of the glove of 150a as shown in FIG. 4 and particularly illustrates the additional pad 252 which is disposed to extend over the pads 152 and 154 and is spaced from the ulnar nerve 102. In the glove 150a an outer palmar side panel 151a is provided to cover the ulnar protective pad 252 and an inner palmar side glove lining 165 is also provided.

In a preferred glove, the pads 152 and 154 are between one-eighth ($\frac{1}{8}$) and one-quarter ($\frac{1}{4}$) of an inch in thickness and generally between one-quarter ($\frac{1}{4}$) and one-half ($\frac{1}{2}$) of an inch in width. The pad 252 also has a thickness of about one-eighth ($\frac{1}{8}$) to one-quarter ($\frac{1}{4}$) inch and is of a sufficient width to extend over the ulnar protective pads 152 and 154.

The gloves 150 and 150a are generally constructed of leather or appropriate flexible synthetic materials. The expansion zones in the gloves 150 and 150a are covered with stretchable or elastic materials, such as, for example, 2-way SPANDEX® which allows flexion of the joints when in use. The protective padding is generally rubber or any appropriate foam or cushioning material well known for glove padding.

The detailed description is given primarily for clearness of understanding and no unnecessary limitations are to be understood therefrom where modifications will become obvious to those skilled in the art upon reading the disclosure and may be made without departing from the spirit of the invention and the scope of the appended claims.

What is claimed is:

1. A glove comprising:
a palmar side panel and a dorsal side panel secured along each panels outer periphery with an opening therein to

receive a human hand; said dorsal side panel being sized to cover the back of said hand and in conjunction with said palmar side panel defining a thumb stall and a plurality of finger stalls for receiving a thumb and fingers of a human hand; said palmar side panel including shock absorbing pads positioned to be along opposed sides of an ulnar nerve in a wrist area of a human hand.

2. The glove of claim 1 said shock absorbing pads including a first ulnar protective pad positioned to be along the medial side of a proximal end of the metacarpal of a little finger of said human hand and at least adjacent to the pisiform in said wrist area and a second ulnar protective pad positioned to be generally between a median nerve and said ulnar nerve in said wrist area of said hand said second ulnar protective pad positioned to be over a portion of the capitate lunate and hamate bones in said wrist area.

3. The glove of claim 2 including palmar protective padding extending over the metacarpals of a plurality of fingers wherein the metacarpalphalangeal joints of said fingers are absent of padding.

4. The glove of claim 2 including palmar side protective padding positioned over the metacarpal of the thumb the metacarpalphalangeal joint being absent of padding.

5. The glove of claim 2 including a third ulnar protective pad positioned to extend over the first and second ulnar protective pads and spaced from said ulnar nerve.

6. The glove of claim 2 said ulnar protective pads having a thickness of from about one-eighth ($\frac{1}{8}$) inch to one-fourth ($\frac{1}{4}$) inch.

7. The glove of claim 2 including shock absorbing pads positioned to be over proximal phalanges of said fingers and between the proximal interphalangeal joints and the metacarpalphalangeal joints; said joints being absent of padding.

8. The glove of claim 2 said thumb element including shock absorbing padding positioned to be along a metacarpal proximal to a metacarpalphalangeal joint and a proximal phalanx distal to said metacarpalphalangeal joint.

* * * * *
